FIG.1

FIG.2

FIG.5

FIG.4

FIGURE 1 is a perspective view of my invention, as it would appear on a reclining chair, as viewed from the front and to one side, the broken lines showing the chair being for illustrative purposes only.

FIGURE 2 is a plan view of the footrest, the rear edge nearest the chair being at the top.

FIGURE 3 is a front elevation view of the footrest, the tapered upper edge portion on the right side being shaded.

FIGURE 4 is a rear elevation view of the footrest.

FIGURE 5 is a side elevation view of the footrest, both sides being identical.

I claim:

The ornamental design for a reclining chair footrest, substantially as shown and described.
